United States Patent Office

Des. 187,691
Patented Apr. 19, 1960

187,691

BUILDING

Peter S. Pedersen, Jr., Chicago, Ill., assignor to Wonder Building Corporation of America, Chicago, Ill., a corporation of Delaware

Application April 9, 1959, Serial No. 55,431

Term of patent 14 years

(Cl. D13—1)

Fig. 1 is a perspective view of a buliding embodying my new design;

Fig. 2 is a side elevational view thereof;

Fig. 3 is a top plan view thereof.

Fig. 4 is a fragmentary perspective view of one end of the building illustrating the doors thereof in open position, and

Fig. 5 is an enlarged fragmentary sectional view taken along the plane of line 5-5 of Fig. 1.

I claim:

The ornamental design for a building, substantially as shown.
